RIDING TOY

Matthew Moustakas, Mercerville, N.J., assignor to
CBS, Inc., New York, N.Y.

Filed Feb. 19, 1974, Ser. No. 443,231

Term of patent 14 years

Int. Cl. D21—01

U.S. Cl. D34—15 AJ

FIG. 1

FIG. 2

FIG. 3

FIG. 1 is a front perspective view of a riding toy showing my new design;

FIG. 2 is a bottom plan view thereof; and
FIG. 3 is a rear elevational view thereof.

I claim:

The ornamental design for a riding toy, substantially as shown.
